UNITED STATES PATENT OFFICE.

WILLIAM RABBE, OF CINCINNATI, OHIO.

GLUING-MACHINE.

SPECIFICATION forming part of Letters Patent No. 267,932, dated November 21, 1882.

Application filed June 22, 1882. (No model.)

To all whom it may concern:

Be it known that I, WILLIAM RABBE, a citizen of the United States, and a resident of Cincinnati, in the county of Hamilton and State of Ohio, have invented certain new and useful Improvements in Gluing-Machines, of which the following is a specification.

My invention relates to an improved gluing-machine which is especially adapted to lay or evenly spread a coating of glue upon one surface of lumber—such as veneering-strips or boards. It is obvious that leather, paper, and other materials may be treated in a similar manner in my improved machine.

15 In the accompanying drawings, Figure 1 is a central longitudinal section of my improvement. Fig. 2 is a top plan view of the machine.

A represents the legs for supporting the main frame of the machine.

B' represent the table upon which the machine is supported while it is being acted upon by the gluing devices.

25 C represents the reservoir for holding the melted glue.

D represents a drum, which is mounted upon a shaft, D', journaled in the frame A' of the machine.

30 E represents the outer surface of the drum, which is shown as being wound with coarse twine or rope. The coarse twine or rope E forms a soft textile covering for the drum, in order to readily take up the glue in the reservoir, and it is wound spirally thereon, so that 35 the glue taken up by the same will be uniformly and effectually spread upon and throughout the entire surface of the sheet of material to be glued.

40 G represents a brush, secured to the frame A' a short distance in the rear of the roller or drum D. This brush is arranged in a plane parallel with the face of the drum D, and located so that the bristles will press against the under surface of the material F after it has been acted on by the roller D. The object of 45 this brush is to secure a uniform coat of glue applied by the roller D. It may be arranged to be adjusted to or from the surface of the material F, so as to apply the requisite amount 50 of pressure to remove any superabundance of coating, in case any is applied to the material by the roller D.

If desired, the reservoir C may be made of metal, and an exterior kettle or pan of similar shape adapted to hold water may surround the 55 reservoir, to which heat can be applied for melting the glue.

I represents a reservoir, which may be employed to hold melted glue, if desired, i representing a gate by which glue is fed into reservoir C.

J represents a driving-pulley, mounted on the shaft J', which is journaled on the frame A of the machine.

K represents a transmitting-gear, which is 65 mounted upon the shaft J' and meshes with the pinion L, which is keyed upon the shaft M.

N represents a feeding-roll, rigidly attached to the shaft M. Roller N and its shaft M are made adjustable vertically by means of the 70 standard O, which is slotted to receive sliding journal-boxes which are attached to a screw, P, and regulated by a thumb-nut, p, so that the surface of the roller N may be adjusted to or from the surface of the table B to correspond with the thickness of the material to be 75 glued.

Q represents a friction-roller, the periphery of which engages with the under face of the material F, to assist in carrying it forward over 80 the gluing-drum.

R represents a pressure-roller, located vertically in an axial plane over the roller D. Its office is to hold the material E in contact with the roller D. It should be made adjustable, 85 so as to accommodate the machine to different thicknesses of material.

I do not wish to confine myself to the exact form of feeding devices used for propelling the material over the gluing-roller, as other equivalent well-known forms of feeding devices may be employed.

I claim—

1. In a gluing-machine, the combination of a glue-reservoir, C, supported by a table or frame, and a glue-transferring drum, D, having its exterior surface wound spirally with a textile material for uniformly spreading the glue on the material to be glued, substantially as described.

2. In a gluing-machine, the combination of a glue-reservoir, C, supported by a table or frame, and a glue-transferring drum, D, having its exterior surface composed of twine or rope

wound in a spiral direction for uniformly spreading the glue on the material to be glued, substantially as described.

3. In a gluing-machine, the combination of
5 a table or frame, a glue-reservoir, C, supported
thereby, feed-rollers for carrying the material
to be glued over the reservoir, a glue-transfer-
ring drum, D, having its exterior surface com-
10 posed of twine or rope wound in a spiral direc-
tion for uniformly spreading the glue on the
moving material, and a brush, G, arranged in

a plane parallel to the face of the drum to press
against the moving material which has been
glued, substantially as described.

In testimony whereof I have hereunto set my ¹⁵ hand in the presence of two subscribing witnesses.

WILLIAM RABBE.
